TEMPORARY CONNECTOR FOR FOLDING CHAIRS

John D. Eves, Cortland, N. Y., assignor to The Brewer-Titchener Corporation, Cortland, N. Y., a corporation of New York

Application September 29, 1955, Serial No. 537,483

5 Claims. (Cl. 155—130)

This invention relates generally to connectors for chairs and more particularly to those connectors designed for the purpose of connecting folding chairs temporarily to one another.

In the utilization of folding chairs, it is often desirable to align the chairs side-by-side in temporary rows. Maintaining adjacent chairs in alignment as persons enter and exit the rows is a difficult problem and various methods and devices for maintaining such alignment have been employed. A portable member can be used to connect folding chairs in alignment if it is specifically designed for that purpose. If a large number of chairs are to be displaced in an area in rows, a connector for aligning adjacent chairs must be simple and easy to handle and operate.

The invention herein disclosed has as its principal object the furnishing of a new temporary connector for folding chairs which is readily attachable to adjacent chairs in order to connect them together and maintain them in alignment.

Another object of this invention is to provide a connector which is light in weight and easily transportable so that it can be placed in position to join adjacent chairs without the use of tools or other appliances.

A further object of this invention is to provide a temporary connector for folding chairs which is complete in itself and inexpensive so that it may be produced and sold at a comparatively low cost.

A temporary connector embodying the invention and the manner of using the same is described herein with references to the drawings in which:

Fig. 1 is a perspective view of a group of folding chairs fastened together in alignment by means of a temporary connector having portions of the connector cut away in order to disclose certain features of its construction;

Fig. 2 is a partially sectional view taken along the line 2—2 in the direction of the arrows as indicated in Fig. 1 showing a connector cooperating with chairs to fasten them together in alignment;

Fig. 3 is a partially sectional view taken along the line 3—3 in the direction of the arrows as indicated in Fig. 1 showing in detail a connector with an end hook mounted thereon applied to the lower front cross-brace of a folding chair;

Fig. 4 is a partially sectional view taken along the line 4—4 in the direction of the arrows as indicated in Fig. 1 showing the connector cooperating with the leg of a chair to enable the clamp of the connector to grip the leg;

Fig. 5 is a perspective view of the connector clamp piece, illustrating the details of its construction; and

Fig. 6 is a partially sectional view of an alternate form of clamp engaging the legs of chairs to fasten them together in alignment.

Folding chair 10, 11, 12 and 13 are shown in alignment in Fig. 1 with connector 14, which is also shown in Figs. 2 through 4, applied to the lower front cross-

2

braces 10a, 11a, 12a and 13a of the chairs 10, 11, 12 and 13 respectively. Connector 14 is a rigid member having a base side 15 and side flanges 16 and 17 extending throughout its length forming a U-shaped channel and is preferably constructed of metal.

Connector 14 has attached thereto in spaced relationship a series of clamps 18. A single clamp 18 is shown in detail in Fig. 5 and is a flat piece of metal substantially rectangular in shape which is bent once at each end 10 to form angles 19 and 20 and then bent again closed to each of the ends to form angles 21 and 22. The reason for this will become obvious when the manner in which the clamp is applied to a folding chair leg is described.

Each clamp 18 contains a hole 23 in its flat central portion which has inserted therein pin 24 which is attached to connector 14 at a weld hole 25 which is one of a group of holes which are disposed in spaced relationship in the base side of the connector. The distance between centers of holes 25 is slightly greater than the distance between the legs of one of the folding chairs which is to be connected. It is possible, in accordance with the teaching herein, to alter the assembly in order to accommodate chairs of various widths and also to vary the spacing between chairs.

25 Pins 24 are attached to connector 14 by welding end 26 of each pin to base side 15 of the connector at a weld hole 25. Pinheads 27 cooperate with springs 28 to yieldingly force clamps 18 away from heads 27 and toward connector 14. Channel 14 has cutouts 29 in its flange sides which are substantially rectangular in shape and which are opposite angles 21 and 22 of clamp 18 when the clamp is in a position horizontal to connector 14 in order to facilitate the use of clamps 18 as will be explained below.

30 35 End hooks 30, which are right angle metal pieces are rigidly fastened to side flange 16 at each of the ends of connector 14 by riveting or otherwise. An end hook 30 is shown in detail in Fig. 3 and it is observed that side 30a is in length approximately one-half the width of cross-brace 10a.

In use, chairs which are to be connected are aligned as in Fig. 1 wherein chairs 10, 11, 12 and 13 are aligned side-by-side. A connector is then brought to the front of these chairs. (It is noted that since four chairs are 40 to be connected together as in Fig. 1, connector 14 is of such length and construction so as to enable the attachment of four chairs. However, a connector for any number of chairs may be constructed according to the spirit and teaching of the invention herein set forth.)

45 50 The clamps 18 are rotated by the user until they lie vertically with respect to the horizontal connector 14. The clamps are then inserted between adjacent legs of adjacent chairs and the connector end hooks are applied to the upper portions of the forward lower horizontal

55 cross-braces 10a and 13a as shown in Fig. 3 with adjacent legs of adjacent folding chairs disposed in cutouts 29. Each clamp 18 is then pressed against the spring 28 which is associated with it causing this spring to contract and the clamp is then rotated from the vertical to the horizontal. When the clamp is horizontal it is released, allowing its spring 28 to expand and causing the clamp to bear on the chair legs which are disposed between it and connector 14 in the cutouts 29 which lie 60 opposite angles 21 and 22 of the clamp. This simple procedure is repeated until all the clamps of a connector are horizontal. The chairs are then held in position by the connector and no further effort is required to align them. Adjacent chairs are maintained in alignment by the action of the springs forcing clamps 18 against adjacent legs of adjacent chairs thereby holding the legs in 65 cutouts 29. Endhooks 30 aid in maintaining end chairs 10 and 13 in alignment with chairs 11 and 12.

In the above description the clamping means is spring pressed and no tools or accessories are required in applying the connector to the cross-braces of the chairs. A second embodiment of a clamping means is shown in Fig. 6 wherein features identical with features illustrated in the preferred embodiment have the same number as that feature had when previously described, but with a prime following. The clamping means shown in Fig. 6 is screw threaded rather than spring pressed and is of greatest utility where it is described to leave the chairs connected for a long period.

In the embodiment illustrated in Fig. 6, clamp 18' is shown with threaded pin 31 inserted in hole 23' and screwed into nut 32 which is welded on clamp 18' adjacent hole 23'. Pin screw-head 33 which is circular and has a diameter greater than the diameter of hole 25' in connector 14', in which it is inserted, cooperates with the base side of connector 14' to prevent the end of pin 31 from slipping through hole 25' and also to provide means whereby a screwdriver may be utilized to rotate pin 31.

In use, clamp 18' is applied to adjacent legs 34 and 35 of adjacent chairs which are disposed in cutouts 29' in connector 14', as in the preferred embodiment. To use this second embodiment, however, threaded pin 31 is rotated by the operator until nut 32 in cooperation therewith has caused clamp 18' to firmly press the chair legs into cutouts 29', thereby causing clamp 18' to bear on the chair legs 34 and 35 which are disposed between it and connector 14'.

Thus, among others, the several objects in the invention as specifically aforementioned, are achieved. Obviously, numerous changes in construction and rearrangement of parts might be resorted to without departing from the spirit of the invention as defined by the claims.

What is claimed is:

1. A temporary connector for folding chairs including in combination an elongated member; clamping members mounted throughout the length of said elongated member, said clamping members being constructed and arranged to bear on adjacent legs of folding chairs disposed between said clamping members and said elongated member when said chairs are positioned adjacent each other; and means to force said clamping members toward said elongated member whereby said clamping members and said elongated member bear against the chair legs disposed therebetween.

2. A temporary connector for folding chairs including in combination a rectangular member; flanges on said rectangular member forming a U-channel with said rectangular member as the base side thereof; clamping members mounted on said rectangular member throughout the length thereof, said clamping members being constructed and arranged to bear on adjacent legs of folding chairs disposed between said clamping members and said rectangular member when said chairs are positioned adjacent each other; cutouts in said flanges shaped to allow insertion therein of chair legs which are disposed between said clamping members and said rectangular member; and means to force said clamping member toward said rectangular member and into said cutouts whereby said clamping member and said flanges bear against the chair legs inserted in said cutouts.

3. A temporary connector for folding chairs of the type which has a horizontal cross-brace between two of its legs including in combination an elongated member; clamping members mounted throughout the length of said elongated member, said clamping members being constructed and arranged to bear on adjacent legs of folding chairs disposed between said clamping mem-

bers and said elongated member when said chairs are positioned adjacent each other; means to force said clamping members toward said elongated member whereby said clamping members and said elongated member bear against the chair legs disposed therebetween; and hooks fastened to said elongated member at each of its ends whereby said elongated member can engage the horizontal cross-braces of chairs which are at the outermost positions of said chairs which are disposed adjacent each other.

4. A temporary connector for folding chairs of the type which has a horizontal cross-brace between two of its legs including in combination a rectangular member; flanges on said rectangular member forming a U-channel with said rectangular member as the base side thereof; clamping members mounted on said rectangular member throughout the length thereof, said clamping members being constructed and arranged to bear on adjacent legs of folding chairs disposed between said clamping members and said rectangular member; means to force said clamping member toward said rectangular member and into said cutouts whereby said clamping member and said flanges bear against the chair legs inserted in said cutouts; and hooking means attached to one of said channels at each of its ends whereby said channel can engage the horizontal cross-braces of chairs which are at the outermost positions of said chairs which are disposed adjacent each other.

5. A temporary connector for folding chairs of the type which has a horizontal cross-brace between two of its legs including in combination a rectangular member; a second rectangular member attached perpendicularly to said first rectangular member at its long edge; a third rectangular member attached perpendicularly to the remaining long edge of said first rectangular member forming a U-channel having said first rectangular member as the base side thereof and said second and third rectangular members as the flanges thereof; clamping members mounted on said first rectangular member throughout the length thereof, said clamping members being constructed and arranged to bear on adjacent legs of folding chairs disposed between said clamping members and said first rectangular member when said chairs are positioned adjacent each other; cutouts in said second and said third rectangular members shaped to allow insertion therein of chair legs which are disposed between said clamping members and said first rectangular member; yielding means to force said clamping members toward said first rectangular member and into said cutouts whereby said clamping members and said second and said third rectangular members bear against the chair legs inserted in said cutouts; and hooking means attached to said second rectangular member at each of its ends whereby said second rectangular member can engage the horizontal cross-braces of chairs which are at the outermost positions of said chairs which are disposed adjacent each other.
